UNITED STATES PATENT OFFICE

ALFRED COPONY, OF MOUNT CLEMENS, MICHIGAN, ASSIGNOR TO GERTRUDE COPONY,
OF MOUNT CLEMENS, MICHIGAN

OILING DEVICE FOR AUTOMOBILES

Application filed December 5, 1928. Serial No. 323,971.

This invention relates to improvements in oiling devices, more particularly for use in connection with automobiles and has for its object the oiling of such parts of the chassis of an automobile that are usually greased or oiled by hand at stated intervals.

A further object of my invention is, to make the greasing of the chassis entirely automatic and independent of the operator.

Another object of this invention is to make the supply of oil to the different parts of the chassis positive in action by supplying oil under forced feed to each individual bearing, thereby eliminating the possibility of clogging as it so often happens in group lubrication.

Another object of my invention is the possibility of regulating the oil supply to the different bearings according to the needs of the chassis on smooth and rough roads, or in new and old machines.

In the drawings:—

Figure 1 represents a vertical cross section through my oiling device, slightly enlarged.

Figure 2 shows a vertical section along line I—II—III of Figure 1, with the spring and spring cap shown in full.

Figure 3 shows a section along curved line II downward as shown in Figure 1 which was enlarged and flattened out for better observation.

Figure 4 shows a vertical section of another variant of my oiling device.

Figure 5 shows a horizontal cross section through the center of Figure 4.

Figure 6 shows a schematic outline of a variation of my invention and

Figure 7 shows a schematic outline of another variation of my invention.

Referring now to the drawings, numeral 1 represents a circular housing, made of brass or bronze which is formed at its right hand upper portion Fig. 1, into a plunger barrel 2 threaded at its upper end. A tempered steel plunger 3 is adapted to move in a vertical direction in plunger barrel 2, and is pointed at its lower end and cut out at its left side to provide an unobstructed admission of oil at any position of the plunger through intake 4 of housing 1. A spring (not shown) and an

intake valve ball 5 are adapted to shut off the flow of oil when the plunger is on the downward stroke. A housing core 6 is placed in the center of the housing adjacent to ball retainer plates 45 which in turn lie in contact with outside plates 16 the whole being fastened by means of tie screws 15 to housing 1 thereby forming a runway 7 of square cross section in which a key ball 11 and smaller idler balls 12 Fig. 1, are afforded free movement in a clockwise direction. The outside plates 16 are recessed to form discharge ports 8 which are connected with oil feed tubes 46 which lead to the different oiling points of the chassis. Each discharge port 8 is equipped with a discharge port ball 9 actuated by a discharge port ball spring 10. Discharge port ball 9 extends slightly into the runway 7 Fig. 3, through a hole provided in ball retainer plate 45 when the vent is closed. By varying the depth to which these discharge port balls extend into the runway I can permanently regulate the supply of oil fed through the oil lines and increase or decrease the amount of oil to be supplied.

Plungers 3 is formed at its upper end into a spring cap 24 which provides an upper bearing for release spring 23 while diaphragm lock nut 18 provides the corresponding lower seat for spring 23. The lower diaphragm 19 is connected to a diaphragm ring 21 which in turn connects with upper diaphragm 20 which carries on its upper surface at the center diaphragm connecting lug 25, which in turn holds rubber shackle 26 in place. Lower diaphragm 19 is provided with a release valve Fig. 2, consisting of diaphragm release valve ball 32 release valve housing 33 and release valve spring 34. Very small intake vents 35 are also provided in lower diaphragm 19. An end shackle bracket 28 provides connection with rubber end shackle 27 which in turn furnishes a pivot point for operating arm 29 on which operating weight 30 is slidably mounted and adjustable by set screw 31.

The whole mechanism is mounted in a convenient place under the hood of the automobile at a height that is above the highest oiling point of the chassis. Assembly bolts 14

provide adequate means for mounting the device to a bracket. Intake valve 5 is conveniently connected by means of intake pipe 37 to an oil feed tank located under the hood. 5 Discharge pipes 46 are in turn connected with all the oiling points of the chassis. My oiling device shown in Fig. 1 is adapted to feed 24 oiling points but an increase in the length of the runway and a corresponding 10 increase in the number of idlers vents and discharge pipes will meet the requirements of a bigger number of oiling points without increasing the size of the plunger.

Figures 4 and 5 show a variation of my oiling device without departing from the main principle involved. In place of using ball idlers 12 Figs. 1 to 3, disk idlers 39 are used which operate in idler grooves 40 Fig. 5, while key ball 11 runs in the original runway 7. The mode of operation is the same as that shown in Figures 1 to 3. Instead of using a diaphragm recoil mechanism as shown in Figures 1 to 3 I attain the same results by using the extension of the stuffing box nut 41 to form an expandible air chamber with compression cylinder 42 and an air vent valve consisting of housing 33 ball 32 and springs 34. A series of weights 44 mounted on the whole piston assembly take the place of lever and counterweight in Figures 1 to 3 and the action of this mechanism can be varied by adding to or removing weights 44. A retainer arm 43 fasten to the housing at its lower end and to retainer arm bracket 38 on counterweight 44 limits the upward motion of the plunger.

Before starting the oiling device for actual use, air vent 36 is opened and the whole oiling system filled by means of an oil tube inserted into filling plug opening 47 until the whole system is filled then plug is inserted and the air vent closed.

In operation my oiling device works as follows:

45 Right after the automobile hits a depression in the road and is on the rebound, operating weight 30 Fig. 1, still persists on the downward path, pushes down the plunger 3 and expells the air from the diaphragm by means of the vent valve on the lower dia- 50 phragm 19. Plunger 3 will compress the oil providing a slight leakage in all the discharge vents by causing the oil to leak past the balls in the square cross section of runway 7 until 55 the plunger hits an idler ball which in turn pushes the whole row of balls ahead until key ball 11 strikes one of the vent balls 9 thereby opening the discharge port of vent ball 9 to receive the full charge of oil displaced by the 60 downward movement of the plunger and after the key ball has slid over the discharge port ball it comes to rest between the one passed and the next discharge port ball in line. The length of the stroke of the plunger 65 depends on the force of the rebound and

is limited only by striking the spring cap 24 on diaphragm lock nut 18, Fig. 1. Just as soon as the plunger has struck the limit of its travel release spring 23 brings the plunger slowly back to its original position due to the fact that the diaphragm release valve ball 32 closes the diaphragm release valve and only a slow seepage of air through intake vents 35 in the lower dia- 70 phragm takes place. Oil is sucked into the pump on this retarded stroke through intake 75 4 and valve 5. When key ball 11 is on the circular portion of runway 7 any backward movement of the key ball is stopped by the locking action of the different discharge port 80 balls 9 with key ball 11, see Fig. 3 dotted position, but, just as soon as key ball 11 has reached the apex of the runway and dropped into the vertical storage chute portion of runway 7 the idler balls 7, being smaller, would have a tendency to roll back due to the increase of weight on the left hand of the runway of the idlers, and flow back towards the plunger. To prevent such a condition idler 85 brake ball 13 comes into action and prevents such an occurrence. After the key ball has dropped into the vertical portion of the runway 7 there will be one or two idler balls 12 ahead of the key ball ready to receive the impact of the plunger and as there is no key ball 90 in the circular portion of the runway all of the discharge balls 9 will lift slightly and provide a general leakage of oil in the oiling system until key ball 11 is once more in operative position. Should the plunger hit one of the balls in such an unforeseen manner that it 95 would jam between the sharp edge of the storage runway and the edge of the plunger, no damage can occur because on the rebound the ball is released and permitted to drop into 100 place after which the regular operation of the balls will resume.

The use of rubber end shackle 27 and rubber shackle 26 eliminates the necessity of oiling the only movable parts of the oiling device not naturally bathed in oil during operation and they will also obviate wear and noise by the use of this medium. If the automobile is regularly driven on rough gravel roads which would speed up the action of the 110 oiler the oiling system can be adjusted by sliding the operating weight 30 Fig. 1, toward the diaphragm and hold it in place by means of set screw 31, while on continuous use on well paved roads an increased sensitivity to shock can be attained by reversing the adjusting operation. Adjustment of the counter weight will be mainly dependent on the consumption of oil desired on the basis of experience and in a new stiff car the counterweight will be set for increased oiling action while later on it will be adjusted for more economic use of oil.

Figures 4 and 5 show a variation of my invention wherein the motion of the idler

disks 39 is confined within the limits of idler groove 40 so that none of the idlers have an opportunity of touching any of the discharge port balls 9. In this case also the retarding of the recoil motion is brought about by the slow seepage of air between extension of stuffing box 41 and compression cylinder 42.

5 My oiling device is subject to a variation of combinations and variation without detracting from the value of my invention.

10 A plurality of key balls can be used without changing the spirit of my invention. For instance a straight runway with a slightly inclined return channel can be substituted for 15 the semicircular course used in Fig. 1 to 5 inclusive which is shown in schematic drawing Fig. 6. This would avoid bunching of the oil lines and easier accessibility of the oiling device and might lend itself to more restricted 20 spaces. Figure 7 shows a schematic layout in a horizontally restricted space.

25 My oiling device lends itself as readily to the oiling of stationary machinery not subject to road shocks by the simple expedient of attaching a motion reducing rocker arm from any reciprocating part of an engine to the plunger, thereby limiting the stroke to a pre-conceived discharge capacity and a regular motion without detracting from the import 30 of my invention.

35 It is also possible to derive the actuating motion of the plunger in automobiles from the chassis springs without materially changing the scope of my invention.

Having thus described my invention, what I claim is:—

1. In an oiling device consisting of a housing, a plunger within said housing, an intake valve within said housing, a plurality of 40 discharge valves normally extending into said housing, and means for actuating said discharge valves successively and progressively by the motion of a key element actuated by idling elements, all propelled by said 45 plunger within said housing.

2. In an oiling device consisting of a housing, a plunger within said housing, an intake valve within said housing connected with an outside oil tank, a plurality of discharge 50 valves connected at their discharge end with oil feed lines the intake end of said discharge valves extending normally into said housing, and means for actuating said discharge valves successively and progressively by the 55 motion and contact with a key element actuated by idling elements, all propelled by said plunger within said housing.

3. In an oiling device consisting of a housing, a plunger within said housing, an intake 60 valve within said housing connected with an outside oil tank, a plurality of discharge valves connected at their discharge end with oil feed lines the intake end of said discharge valves extending normally into a closed end- 65 less runway of said housing, means for actu-

ating said discharge valves successively and progressively by the motion of and contact with key elements actuated by idling elements within said closed endless runway of said housing, both key elements and idling elements being propelled by said plunger 70 within said closed endless runway of said housing.

4. In an oiling device consisting of a housing, a plunger within said housing, means for actuating said plunger outside of said housing, an intake valve within said housing connected with an outside oil tank, a plurality of discharge valves connected at their discharge ends with oil feed lines the intake ends of said discharge valves extending normally into a closed endless runway of said housing, means for actuating said discharge valves successively and progressively by the motion of and contact with key elements actuated by idling elements within said closed endless runway of said housing, both key elements and idling elements being propelled by said plunger 75 within the endless runway of said housing.

5. In an oiling device consisting of a housing, a plunger within said housing, means for transmitting road shocks to said plunger in said housing, an intake valve within said housing connected with an outside oil tank, a plurality of discharge valves connected at their discharge end with oil feed lines and extending normally with their intake ends into a closed endless runway of said housing, means for actuating said discharge valves successively and progressively by the motion of and contact with key elements actuated by idling elements within said closed endless runway of said housing, both key elements and idling elements being propelled by said plunger 80 within the endless runway of said housing.

6. In an oiling device consisting of a housing, a plunger within said housing, means for transmitting road shocks to said plunger in said housing and means for retarding the recoil of said plunger in said housing, an intake valve within said housing connected with an outside oil tank, a plurality of discharge valves connected at their discharge end with oil feed lines and extending normally with their intake end into a closed endless runway of said housing, means for actuating said discharge valves successively and progressively by the motion of and contact with key elements actuated by idling elements within said closed runway of said housing, both key elements and idling elements being propelled by said plunger 85 within the endless runway of said housing.

7. In an oiling device consisting of a housing, a plunger within said housing, means for transmitting road shocks to said plunger in said housing and means for retarding the recoil of said plunger in said housing, an intake valve within said housing connected with an outside oil tank, a plurality of discharge valves connected at their discharge end with oil feed lines the intake end of said discharge valves extending normally into a closed end- 90 less runway of said housing, means for actu-

ALFRED COPONY.
